BELT FOR PREVENTING RELATIVE MOVEMENT BETWEEN TWO GARMENTS

Sidney Louis, Chicago, Ill.

Application March 20, 1950, Serial No. 150,740

1 Claim. (Cl. 2-320)

1

My invention relates to belts. More particularly my invention relates to elastic belts designed to minimize relative movement between two garments overlapping at the waist.

Both men and women commonly wear a combination of garments, such as shirts and trousers or blouses and skirts, which require the upper garment to be tucked into the lower garment. Engaging in physical activity while wearing such an attire frequently causes the upper garment to become disengaged or the bottom garment to become twisted. Such relative movements of these garments may cause an untidy appearance. This problem is especially acute in the case of blouses and skirts, since the blouses are generally quite short, while the skirts have a tendency to slip downward or rotate.

It is therefore an object of my invention to provide a belt, which when worn around the waist between two over-lapping garments prevents their relative slipping or twisting.

It is another object of my invention to provide a flexible belt which can be snugly fitted and yet is not uncomfortably constricting.

It is a further object of my invention to develop a means for fastening a belt which is strong, yet comfortable and inconspicuous, and which permits adjusting the belt to different size waists.

A still further object of my invention is to provide a belt which is ventilated to prevent perspiration or irritation of the skin, and which can be easily washed.

Another object is to provide a belt of the character described which is inexpensive yet long wearing.

The foregoing objects are fully achieved in my novel belt, which comprises a strip of elastic material such as crepe rubber, having at least one lengthwise row of holes and pegs arranged in an alternating pattern, and a fastener attached to one end of the strip in a position a peg might occupy, said fastener including an enlarged flat headed portion adapted to be inserted through one of said holes in said belt upon stretching thereof. By the term "alternating pattern" I mean an arrangement of holes and pegs within each row whereby a sequence such as that of hole-peg-hole-peg, peg-peg-hole-hole is established and maintained throughout any individual row.

In order that my invention may be more fully disclosed, reference is had to the accompanying drawing which illustrates one form of belt embodying the foregoing and such other principles,

advantages or capabilities as may be pointed out as this description proceeds, or as are inherent in the present invention. For purposes of clarity in exposition, the following description is explicit, and the accompanying drawing is detailed, but it is distinctly to be understood that said exposition is illustrative only, and that my invention is not restricted to the particular details recited in the specification or shown in the drawing.

2

In the drawing:

Figure 1 is a schematic view showing how my belt is placed around the waist of the wearer preparatory to fastening it in place;

Figure 2 is a schematic view showing the belt of Figure 1 after being fastened in place;

Figure 3 is a schematic view showing the front of the belt of Figure 1 after being fastened around a waist with an outer garment being placed over it;

Figure 4 is a fragmentary, detail view of the front of my belt as it appears when fastened in place;

Figure 5 is a side view of my belt taken in section on the line 5—5 of Figure 4; and

Figure 6 is a side view taken in section on the line 6—6 of Figure 4.

Like reference numbers designate like parts in the drawing and in the description of my invention which follows.

Referring now to the drawings and more particularly to Figure 4 thereof, my belt is shown as including a strip 10 of flexible elastic material having a plurality of rows of transverse holes 14 and approximately hemispherical pegs 15 arranged in an alternating pattern. Within each row the holes 14 and pegs 15 are substantially uniformly spaced and dimensioned and as shown in Figure 6, the pegs 15 extend outwardly about as far as the strip is thick. In the pattern illustrated in Figure 4, pegs 15 are located approximately midway between adjacent holes 14. However, this spacing, while preferred, is not critical; for example each peg 15 could be located closer to one adjacent hole 14 than to the other, providing the displacement is uniformly maintained in each individual row. Likewise, Figure 4 shows three longitudinal rows so aligned that holes 14 and pegs 15 form a plurality of vertical rows of alternating holes 14 and pegs 15. It is apparent, however, that neither a particular number of longitudinal rows, nor an alignment in vertical rows is critical to the functioning or principle of my invention.

As best shown in Figure 5, the outer end por-

tion 12 of strip 10 includes a flanged hole 13. As viewed in Figure 4, the flanged hole 13 is located in the center longitudinal row at a distance from the nearest peg 15 in that row equal to the uniform distance between adjacent pegs 15 in that row; that is, the flanged hole 13 is located in the center row in a position that a peg 15 would occupy if the alternating pattern of pegs and holes extended from end to end with complete uniformity. A fastener 16 is secured in the flanged hole 13, and includes an enlarged, button-like head portion 17 and a retainer flange 18.

The use of my belt is illustrated in Figures 1, 2 and 3. More particularly, the strip 10 is first placed around the waist over a garment, such as the blouse 19. The end portion 12 of the strip 10 is then pulled over the end portion 11, to place the strip 10 under tension and to secure a snug fit about the waist. Next, the head portion 17 of the fastener 16 is forced through the nearest hole 14 in the center row of the end portion 11. Since the strip 10 is of a stretchable material, said hole 14 in the end portion 11 may be temporarily deformed to permit the insertion of the head portion 17 therethrough.

Advantageously, the pegs 15 on that section of the end portion 11 which overlaps the end portion 12, are aligned with and extend into holes 14 in said end portion 12. As a result of this interlocking of the pegs 15 in the holes 14, the forces acting on the strip 10 by virtue of its stretched configuration, are distributed over the entire overlapping portions 11 and 12 of the strip 10. Thus, the load placed on the fastener 16 may be held to within safe limits, with the result that the strip 10 does not split at the hole 13, even though the tension on the strip 10 is unusually great. Moreover, the head portion 17 of the fastener 16 is flat and of thin cross-section, so that there are no inner projections on the strip 10 to render the belt uncomfortable to wear.

After the strip 10 has been positioned upon the blouse 19 in the manner shown in Figure 2, the outer garment, such as the skirt 20, is put on over strip 10 in engagement with the pegs 15. In one commercial embodiment of my invention, the pegs 15 project outwardly about $\frac{1}{8}$ inch, so that they firmly grip the skirt 20 to prevent relative movement between said skirt 20 and the blouse 19, yet do not show through the material of the skirt 20.

Advantageously, my belt can be inexpensively molded from conventional synthetic or natural rubber mold mixes. I prefer, however, to use crepe rubber, since it has an especially high coefficient of friction for cloth. Moreover, crepe rubber normally has, or may easily be given, a somewhat roughed surface, which is advantageous in increasing the amount of friction between my belt and the inner garment over which it is worn.

Having thus fully described my novel belt, and demonstrated its utility by reference to a specific embodiment thereof, I claim as my invention:

A belt to be worn about the waist between two garments in order to guard against slippage of said garments, consisting of a single flexible strip of crepe rubber of greater length than the circumference of the waist, one side of the strip being without protuberances but having a rough surface whereby it will frictionally grip an inner garment, the other side of said strip having integrally formed therein and longitudinally substantially coextensive therewith at least one row of protuberances, said strip being perforated with at least one row of holes, said holes being in a substantially uniformly alternating pattern with said protuberances, the protuberances being approximately hemispherical and extending outward from one surface of the strip approximately the thickness of said strip, whereby when the ends of the strip are overlapped, the protuberances on one side of the overlapping portion of said strip can readily be inserted into and engaged by the holes in the overlapping portion of the other end of said strip, one end of the strip having a centrally located fastener hole in place of one of said alternating protuberances, said end of the strip having a substantially rigid fastener in said fastener hole and adapted to be inserted in a matching centrally located hole in the other end of said strip.

SIDNEY LOUIS.
